WRINGER MECHANISM

Nicholas L. Etten and Fred A. Christensen, Waterloo, Iowa; said Etten assignor to Chamberlain Corporation, Waterloo, Iowa

Application March 19, 1932, Serial No. 600,022
Renewed June 24, 1937

13 Claims. (Cl. 68—263)

This invention relates to wringer mechanism.

One of the objects of the invention is in the provision of a manually operated safety mechanism for relieving the tension between the roll members of a clothes wringer, said mechanism being adapted to operate instantly, irrespective of the manner in which it is moved.

Another object lies in the provision of safety release mechanism for the roll members of a clothes wringer, said wringer being adapted to be manually operated to relieve tension whether moved laterally or downwardly by the operator.

Still another object lies in the provision of a wringer mechanism comprising a lower frame adapted to receive the wringer roll members, an upper frame detachably connected to the lower frame, said upper frame carrying the pressure applying means between the rolls, and a safety release mechanism normally holding the upper frame and lower frame in an operative position, said safety release mechanism including a manually operated latch mechanism capable of release by the operator, irrespective of the manner of movement thereof by the operator.

A further object lies in the provision of a safety release mechanism for controlling the release of tension between the rolls of a wringer, said safety release mechanism including latch mechanism so arranged as to be capable of release, irrespective of the manner of direction of release by the operator.

A still further object lies in the provision of a wringer mechanism comprising a lower frame adapted to receive the conventional wringer rolls, an upper frame capable of detachable relationship with the lower frame, tension applying means for the roll, a safety release mechanism for relieving the tension between the rolls, and means for preventing complete removal of the upper frame from the lower comprising hanger members connected to the upper frame and having a sliding connection with the lower frame.

Other objects will appear in the following specification, taken in connection with the annexed drawings, in which—

Fig. 1 is a plan view of the wringer;

Fig. 2 is an end elevation thereof;

Fig. 3 is a partial side elevational view;

Fig. 4 is an enlarged sectional view taken on the line 4—4 of Fig. 11;

Fig. 5 is an enlarged view taken on the line 5—5 of Fig. 3;

Fig. 6 is an enlarged detail showing of the manually operated tension release member;

Fig. 7 is a plan view showing the universal pivot of the safety release mechanism;

Fig. 8 is an elevational view showing in section various portions of the wringer;

Fig. 9 is a sectional view taken on the line 9—9 of Fig. 8;

Fig. 10 is a cross-sectional view taken on the line 10—10 of Fig. 8; and

Fig. 11 is a sectional view taken on the line 11—11 of Fig. 8.

Before referring specifically to the drawings, for a detail description and disclosure of applicants' wringer, it might be well to explain generally the main features of the wringer in view of the prior art and the general class of wringer devices now appearing on the market.

Wringers have become standard to the extent that they comprise a frame mechanism, dual wringer rolls disposed either in a horizontal or vertical position, means for applying tension between the rolls and finally and essentially, some means for effecting an instant release of the tension in case of accident. It is this safety feature to which the present invention is directed.

The prior art is replete with safety devices for releasing tension between the rolls. Efforts directed from many angles have been made to provide a manually operated release member which was not only in a position to be readily struck by the operator but one which operated easily and instantly. Various individuals have disposed their release members upon practically every side or surface of the wringer; however, in every instance, these release members have required manual operation by the operator.

Applicant herein has disposed his release mechanism upon the upper frame of the wringer in a position to be readily struck by the operator. Generally, as far as the mounting is concerned, it is conventional, with the exception that there has been taken into consideration the fact that in case of accident the operator being in a highly nervous and frightened condition, is not mentally in a state of mind to act normally. In other words, these safety release members require a certain directional movement to accomplish the release of tension between the rolls.

Ordinarily, the practice is to force a lever in a lateral manner. Other release mechanisms require a downward striking of the safety release. In the present instance, applicant has provided not only an instantly releasable latch mechanism but, of more importance, one that when struck from any direction or in any manner, will instantly relieve the tension between the rolls.

It is believed that this mounting of the manually operated safety release mechanism in a universal manner marks an important development and step forward when safety release mechanism for the conventional type of wringer is concerned.

Now, referring specifically to the drawings, a U-shaped wringer frame is made up of the horizontal base 10 and uprights or end portions 11 and 12. In the present instance, this frame is formed by a stamping operation and may be either riveted or welded together. The end plates or uprights 11 are so fashioned as to receive therein the upper and lower pairs of wood bearing blocks 13 and 14 respectively, which are slidably mounted within the uprights. These uprights are also slotted inwardly in a manner to receive the projecting ends of the shafts 15 and 16 upon which the rubber roll portions 17 and 18 respectively are mounted.

So far merely conventional wringer construction has been described. The detachable upper frame of the wringer is also conventional in general formation, in that it comprises a stamped portion or upper frame 19, which is adapted to fit or nest at either end upon the upper ends of the uprights 11 and 12.

Laterally projecting pairs of ears 20 and 21 upon the uprights 11 and 12 define the relative position of the upper frame 19 with respect to the uprights. The upper frame carries a conventional horizontal roll tensioning spring 22, the position and tension of which is in turn controlled by a tensioning screw 23 having a clamp 24 at its lower end carrying the spring 22. The member 23 has a threaded relation 25 with the frame and is operated by means of a conventional manually operated portion 26.

The manner of attaching the upper frame to the lower frame upon one side includes the outwardly turned lip 27, which is struck from the upper end of the upright 12 and an overlapping, similarly shaped member 28, which is struck from the outer end of the frame 19.

It is apparent that the above described members merely comprise a simple detachable connection between one end of the frame 19 and the upright 12. The construction is entirely conventional.

The upper and lower wooden bearing blocks 13 and 14 are, as previously described, slidably contained in the vertical uprights 12. The upper and lower bearings upon the opposed side are likewise slidably contained in the upright 11. However, the opposite side of the frame 19, although removable to a certain degree from the upright 11, nevertheless is connected thereto in the following manner. A bolt 29 passes laterally through the upper frame 19. As shown in the drawings, this comprises a screw member having a threaded nut 30 upon its opposite end. Obviously, this bolt is a hanger member and might be connected to the frame in any manner desired.

Loosely hung, as at 31, upon this screw 29 are dual hanger members 32 and 33, which pass downwardly within the upright 11 and both have the longitudinal slotted portions 34. Dual lugs, 35, fixedly secured to the sides of the upright 11 have portions 36 projecting into the before mentioned slots 34 in such manner that the members 32 and 33 are slidably carried upon these lugs, with the result that the frame 19 is permitted vertical displacement with respect to the frame at this end, a distance which is defined by the length of the slots 34. However, absolute detachment of the upper frame with respect to the low-

er frame on this side is prevented. Such attachment of the upper frame with the lower frame is provided in order to prevent the complete removal of the upper frame with respect to the lower frame when the safety mechanism, later to be described, has been released. It will be noted, however, that the opposite end of the frame is completely detached from the upright 12.

Laterally disposed pins 37 and 38 define the position of the lower wringer roll shaft 16, which as will be noted by the projecting end 39 thereof, is the power roll which is connected to the conventional driving source.

That is to say, the hangers 32 and 33 are loosely and pivotally suspended from the cross member 29. This pivotal suspension of the hangers, combined with the pin and slot connection between the hangers and the frame, allows the hangers to partake of a limited pivotal movement as an incident to the upward movement of the head 19. Clearly, as the head 19 moves, the hangers 32 and 33 will have to partake of a limited swinging movement of the adjacent uprights and this is allowed by the more or less free connection of the hangers not only to the frame but to the head.

Now, with respect to the safety mechanism or quick detachable mounting of the upper frame 19 with respect to the U-shaped wringer roll receiving frame of the wringer, a stamped metal bracket 40 has its bifurcated end portions 41 and 42 apertured in a manner to engage the screw 29 which, as previously described, carries the hanger portions 32 and 33. This bracket is further riveted in the dual manner, as shown at 43, to the end of the frame 19. It also provides bearing support for a laterally disposed rod or bar 44 which in turn carries the roller member 45.

As will be seen, perhaps most clearly in Fig. 5 of the drawings, a portion of the end of the frame 19 is cut away as at 46 to permit slight projection of the roller 45. In other words, the roller projects through the aperture 46 and defines the normal curve between the top of the frame 19 and the downwardly projecting end 47 thereof.

A latch portion 48 has the dual ear portions 49 overlapping the upright 11 and being pivotally connected thereto in the dual manner shown at 50. This latch is curved as at 51 to conform with the curve of the roller which it immediately overlies when in a normal position. An upwardly projecting rounded engagement lug is shown at 52.

The opposed latch portion, and it might be said the manually operated release member, comprises the following parts. A lug engaging latch member 53 has formed as an integral part there-with a manually operated safety release handle or member.

The latch and release portion 54 has a novel connection with the frame. In the first place, the intermediate portion 55 of the release mechanism is so fashioned as to receive a laterally disposed upper end portion 56 of a downwardly projecting pivot 57, which portions complete the connection between the release member and the frame 19. The laterally projecting pin or member 56 holds the safety release member 54 in a frictional manner against the frame 19; however, the portion 55 which surrounds the pivot 57 is apertured sufficiently to permit movement of the release member in a vertical manner, as shown by the dotted lines in Fig. 8 of the drawings.

It will be noted that the release member 54 is 75

normally held in an upward and tensioned position by means of the flat tension spring 58, which abuts the under side of the member 54 at one end, said spring being carried at its opposite end 59 upon the pivot 57 and in a position between the release member and the frame. It will be noted further that the safety release member is not only permitted an upward and downward movement, but also, due to the pivoting relation of the release upon the frame 19, it is permitted a lateral movement in either direction, as perhaps most clearly shown by the dotted lines in Fig. 1 of the drawings.

The before mentioned opposed latch portion 53 is slightly rounded or cam fashioned to permit ready engagement with the vertical projected rounded lug 52 when the release member is secured by lateral movement. It is thought apparent, however, that the final connection between the frame 19 and upright 11 is accomplished by either connecting the latch 53 to the lug 52 by a vertical method of connection, or by a lateral method of connection, as is desired. In other words, the safety release member 54 has a universal mounting with respect to the frame 19 and is capable of latch connection with the opposed latch portion 51 either by vertical depression of the member 54 and subsequent downward movement to an engaged position or by lateral movement of the member 54 to a position where the latch 53 engages the rounded vertical lug 52.

It will be noted that the roller has been placed immediately beneath the latch 51 in such manner that there will be no frictional resistance to the movement of the latch 51 towards the opposed latch portion. The latch connection might well be made without this roller portion, although it is believed apparent that by using this anti-friction roller the movement of the portion 51 to a latched position is assisted materially by this mechanism.

Now, with respect to the operation of applicants' mechanism, in the first place, the wringer generally is constructed along conventional lines and it is apparent that the novel features of applicants' wringer reside in the manner of latching the frame with respect to the upright 11. The opposite end of the frame 19 is connected to the upright 12 in the conventional manner and when it is desired that the other end of the frame 19 be connected to the upright 11, it is apparent that the operator has the option of latching the relative portions either by a vertical or a lateral movement.

As far as release mechanisms are normally concerned, it is believed that in every instance it will be found that a single direction of movement of the latching mechanism is required. The latching of the relative portions is materially assisted by the use of the roller, which defines the curve between the end and top of the wringer frame.

The more important feature of this release mechanism resides in the release portion. Since the latch or retaining member 51 engages the roller 45 at a point which is offset to the left, in Figure 8, from the line of force holding the frames together and extending through the axis of the pivot 50 and the roller 45, the retaining member 51 is unstable or unbalanced and is biased toward a release position. Were it not for the second retaining member 53, the first latch would release, but the member 53 retains the latter in holding position. The wringer

normally is adapted to be maintained in a tensioned position and in a latched position; however, in case the operator unfortunately has his or her fingers caught between the rolls in the act of feeding the wet clothes therethrough, it is merely necessary to strike the release member 54 from any direction to release the tension between the rolls. Should the operator be in a position to strike downwardly upon the member 54, the relief of tension will take place. Should the operator in an excited moment, simply strike at the release member 54, irrespective of the position of the operator or the manner of striking the manual release member, whether it be in a lateral or vertical position, instant release of the tension will take place.

It might also be noted, as far as this wringer is concerned, that one end of the frame is entirely detachable from the upright 12 while the opposite end and the end carrying the safety release mechanism is carried in a removable relationship with respect to the frame, but not in an entirely detachable manner by virtue of the slotted relationship and connection of the hangers 32 and 33 with the inwardly projecting lugs 35 formed on the sides of the upright 11.

What we claim is:

1. A wringer mechanism including in combination a lower frame, upper and lower wringer rolls disposed therein, a top bar, means carried by the top bar for applying pressure between the rolls, means for detachably connecting the top bar to the lower frame and a safety release mechanism including a pivoted retaining member on the lower frame, a manually operated retaining member carried by the top bar and cooperating with the first mentioned retaining member, said manually operated retaining member being mounted for movement about a plurality of axes to permit release of the pressure between the rolls when the manually engageable portion thereof is moved downwardly or sidewise.

2. A wringer mechanism including in combination, a lower frame, an upper frame, upper and lower wringer rolls, means for applying pressure between the rolls, and safety release mechanism for relieving the pressure between the rolls, said mechanism comprising cooperating retaining members upon the lower and upper frame members, one of said retaining members being manually operated and being mounted for movement for about plural axes to permit instant release of said pressure when the manually engageable portion of said last mentioned retaining member is moved downwardly or sidewise.

3. A wringer mechanism including in combination a lower wringer frame, a detachable top bar, wringer rolls carried by said frame, pressure applying means, a latch mechanism for maintaining the top bar and lower wringer frame in normal operative engagement, said latch mechanism including a manually operated latch member and a mounting for said latch member permitting movement of said manually operated latch member in a vertical or lateral manner to accomplish the relief of pressure by detachment of the top bar from the lower wringer frame.

4. A wringer mechanism including in combination a lower wringer frame, wringer rolls carried thereby, a detachable top bar, spring pressure means in said top bar, and latch mechanism for holding the top bar and lower wringer frame in a normal operative position with pressure between the wringer rolls, said mechanism including co-operating latch members upon the lower

frame and top bar and a mounting for one of said latch members permitting movement of the latch in either a vertical or lateral direction to accomplish detachment of the top bar from the lower frame.

5. A wringer mechanism including in combination a lower wringer frame, wringer rolls carried thereby, a top bar, pressure means for the wringer rolls, means for releasably associating the top bar with the lower frame including a retaining member pivoted to the lower frame, a second manually operated retaining member carried by the top bar and co-operating with said first mentioned retaining member to hold the top bar 10 and lower wringer frame in a normally fixed position and a roller member carried by the top bar and co-operating with said first mentioned retaining member to assist in the releasing operation.
10. 6. In a wringer, the combination of a frame; rolls mounted in the frame; pressure mechanism for the rolls; a safety release device releasing pressure on the rolls; a release handle having downward and sidewise release movements; and 15 means responsive to said movements of the handle actuating the release device.

7. In a wringer, the combination of a frame; rolls mounted in the frame; a top bar having a hinge engagement at one end; pressure mechanism 20 operating from the top bar on the rolls; a safety release device comprising a release mechanism for the end of the top bar opposite the hinge; a release handle having vertical and sidewise release movements; and means responsive 25 to said movements of the handle actuating the release device.

8. In a wringer, the combination of a lower frame, an upper frame, roll wringing means mounted in the frame, pressure mechanism for 20 the roll wringer means reacting against the upper frame, and safety mechanism for releasably attaching the upper frame on the lower frame, said safety mechanism including a latch member pivoted on one of said frames and having a cam 45 face engaging a part associated with the other frame holding the frames in normal operating position but biased into a release position by the said pressure mechanism, and a second latch member movably attached to said other frame to 50 engage the first latch to resist the biasing of the first latch into said release position.

9. In a wringer, the combination of a lower frame, an upper frame, roll wringing means mounted in the frame, pressure mechanism for 55 the roll wringer means reacting against the upper frame, and safety mechanism for releasably attaching the upper frame on the lower frame, said safety mechanism including a latch member pivoted on said lower frame and having a cam 60 face engaging a part associated with the upper frame holding the frames in normal operating position but biased into a release position by the said pressure mechanism, and a second latch member movably attached to the upper frame to 65 engage the first latch to resist the biasing of the first latch into said release position.

10. In a wringer, a frame structure having, in combination, a lower frame member, an upper frame member movable upwardly with respect 70 to and above the lower frame member, roll wringer means mounted in the frame structure, pressure mechanism for the roll wringer means reacting between the frame members, and safety mechanism for releasably securing the upper and lower frame members together, said safety mech-

anism comprising a retaining member mounted on and movable with respect to one of said frame members and having a portion engaging a part associated with the other frame member for holding the frame members together in normal 5 operating position against the reaction of said pressure mechanism, the engagement of said retaining member with said part being offset with respect to a position wherein said retaining member and part would lock said frames together, whereby the engagement of said retaining member and part is unstable as against the reaction of said pressure mechanism, and a second retaining member movably attached to the other of said frame members for engaging 10 the first retaining member releasably to secure the first retaining member in holding position to lock said frames together.

11. In a wringer, a frame structure having, in combination, a lower frame member, an upper 20 frame member movable upwardly with respect to and above the lower frame member, roll wringer means mounted in the frame structure, and safety mechanism for releasably securing the upper and lower frame members together, said 25 safety mechanism comprising a retaining member mounted on and movable with respect to one of said frame members for holding the frame members together in normal operating position, means for constantly urging said retaining 30 member away from a position where said member would lock said frame members together and for reacting between the rolls and the upper frame member, whereby said retaining member is unstably mounted with respect to a holding 35 position, and a second retaining member movably attached to the other frame member for engaging the first retaining member releasably to secure the latter in holding position, whereby upon movement of the second retaining member 40 to release the first retaining member and permit separation of the frame members by said means reacting between the rolls and the upper frame member, the retaining members are free to move with the respective frame members. 45

12. In a wringer, the combination of a lower frame comprising a base and spaced upwardly projecting end members terminating in free upper ends, a unitary, horizontally disposed top frame mounted at its ends upon and above the 50 free ends of said end members and bridging the space therebetween and releasably secured at one of its ends to one of said end members, wringer rolls mounted in the lower frame, and safety mechanism for releasing said one end of the top frame for movement away from and above said one of the end members, said safety mechanism comprising a retaining member movably mounted at said one end of one of said frames for holding the top frame on the lower 60 frame in normal operating position, means reacting against the top frame for applying pressure between the wringer rolls and for constantly urging said retaining member away from a position where said member would lock said frames together, whereby said retaining member is unstably mounted with respect to a holding 65 position, a second retaining member movably mounted upon the corresponding end of the other frame for engaging the first retaining member to secure the latter in holding position, and means for disengaging the first and second retaining members to permit movement of the first retaining member and release of the top frame from 70 75.

the lower frame under the influence of said means reacting against the top frame.

13. In a wringer, a frame structure having in combination, a lower frame member, an upper frame member movable upwardly with respect to 5 and above the lower frame member, wringer rolls mounted in the frame structure, a retaining member mounted on and movable with respect to one of said frame members for holding the frame 10 members together in normal operating position, mechanism including spring means for applying pressure to the rolls and for constantly urging said retaining member away from a position where said member would lock said framed mem-

bers together, whereby said retaining member is unstably mounted with respect to a holding position, and a second retaining member movably attached to the other frame member for engaging the first retaining member releasably to secure the latter in holding position, whereby upon movement of the second retaining member to release the first retaining member and effect separation of the frame members by said mechanism, the retaining members are free to move 10 with the respective frames.
